EXPLOSION PROOF FLAME TRAP AND DRAIN

Willard E. Parish, Syracuse, N. Y., assignor to Crouse-Hinds Company, Syracuse, N. Y., a corporation of New York

Application August 3, 1953, Serial No. 371,979

5 Claims. (Cl. 138—42)

This invention relates to a combination flame trap and drain for conduit fittings in electrical systems.

The invention has as an object a device of the type referred to embodying a structural arrangement which is particularly economical to manufacture and assemble and, when assembled, providing a flame path of restricted but uniform dimension to efficiently cool the ignited gases, all whereby in the event the device becomes plugged or clogged it may, because of its exceedingly low cost, be thrown away or disposed of and a new device substituted in its place.

The invention consists in the novel features and in the combinations and constructions hereinafter set forth and claimed.

In describing this invention, reference is made to the accompanying drawings in which like characters designate corresponding parts in all the views.

In the drawings—

Figure 1 is a bottom plan view of a flame trap and drain embodying my invention.

Figure 2 is a vertical sectional view taken on line 2—2, 35 Figure 1.

Figure 3 is a view taken on line 3—3, Figure 2.

The device consists of a cylindrical body member 10, the outer end portion 11 of which is of slightly greater dimension and having a periphery of hexagonal formation. The inner portion of the body is threaded externally for attachment to a conduit fitting 12. The purpose of the hexagonal head portion 11 is for application of a wrench to tighten the drain into the conduit fitting.

The body is formed with an axial bore extending inwardly from the inner end of the body and communicating with a radial or transversely extending passage 13 formed in the outer end portion of the body. A series of cup-shaped members 14 are arranged in the bore in stack formation, and the bottom wall of each of the cup-shaped members is formed with an aperture 15.

A disk 16 is positioned in each of the cup-shaped members 14. These disks are imperforate and are provided with means for centering the disks axially in the cup-shaped members. Preferably, the disks 16 are formed on each side with a plurality of projections 17. The disks 16 are materially greater in diameter than the apertures 15 formed in the bottom walls of the cup-shaped members. The disks are of polygonal form and dimensioned so that the points 18 of the polygon engage, or are in close proximity to, the inner surfaces of the flanges of the cup-shaped members, whereby the spaces 19 between the sides of the polygon and the flange of the cup-shaped members provide a number of paths through which the exploded gases may travel outwardly from within the fitting 12. The projections 17 may be conveniently formed by pressing dimples into the disks simultaneously with the blanking of the disks from sheet metal.

The innermost cup-shaped member is closed by a washer 21 which is engaged by a radial flange 22 formed on a tubular member 23. The flange of the tubular member is maintained against the stack formation by a snap ring

2

24 engaging the inner side of the flange 22 and being positioned in a circular groove formed in the bore of the body.

Preferably, the inner portion of the body bore is of increased diameter as indicated at 25, the space between the tubular member 23 and the inner end of the bore forming a well for the accumulation of dirt and sludge which otherwise might be carried into the stack formation and cause the space between the disks 16 and the cup-shaped members to become clogged.

The outer end portion of the body is encircled by a band 26 arranged in registration with the radial passage 13 and spaced outwardly therefrom, the lower edge of the band terminating remote from the enlarged head portion 11 to provide a circular discharge opening for the escape of gases. The purpose of the band 26 is to lessen the possibility of the radial passage 13 becoming plugged up, as by the device being painted.

As constructed, the body of the fitting is formed by a simple screw machine operation. The cup-shaped members 14 and the disks 16 are most economically produced by punch press operation. Due to the polygonal shape of the disks 16 and the projections 17, the disks are centered both radially and axially in the cup-shaped members to provide a passage of uniform area for the escaping gases, thus eliminating any inaccuracy in the assemblage of the parts. This device, because of its novel structural arrangement, can be manufactured at a cost of a few cents whereby, in the event that the device does become wholly or partly clogged, it can be thrown away and a new device substituted in its place. This avoids labor time in disassembling and cleaning the device and effects assurance of a properly operating device.

What I claim is:

1. A combination flame trap and drain for electric conduit fittings comprising a body adapted for flame tight attachment to a conduit fitting, said body being formed with an axial bore extending outwardly from the inner end of the body, the outer end portion of the body being formed with a radially extending passage communicating with the outer end of said bore, a series of cup-shaped members arranged in stack formation in said bore and with their cylindrical flange portions engaging the side wall bore, each of said cup-shaped members having an aperture in the bottom wall thereof, an imperforate disk positioned in each of said cup-shaped members, said disks being substantially complementary in diameter to the internal diameter of the flanges of said cup-shaped members, each of said disks being formed with a plurality of projections on each side, and having at least a part of its peripheral portion spaced inwardly from the flange of the cup-shaped member in which it is positioned, and means operable to retain said stack formation in said bore.

2. A device as defined in claim 1 wherein the diameter of said disks is greater than the diameter of the apertures formed in the cup-shaped members.

3. A device as defined in claim 1 wherein the disks are of polygonal shape.

4. A device as defined in claim 1 having a band encircling the outer end portion of the body in registration with said radial passage and being spaced radially outward therefrom.

5. A combination flame trap and drain for electric conduit fittings comprising a cylindrical body member externally threaded at its inner end for attachment to a conduit fitting, said body being formed with an axial bore extending outwardly from the inner end of the body and communicating with a radial passage formed in the outer end portion of the body, a series of cup-shaped members positioned in said bore in stack formation, each of said cup-shaped members being formed with a central aperture in the bottom wall thereof, a baffle disk positioned in each

of said cup-shaped members, said disk being formed with projections on opposite sides thereof to maintain said disk in spaced relation to the bottom walls of said cup-shaped members, said disks being also formed with projections on their peripheries engaging the side walls of said cup-shaped members, a tubular member positioned in the inner portion of said bore and being formed with a radial flange engaging the inner end of said stack formation, and means carried by the body for holding the flange of said tubular member against the stack formation.
